UNITED STATES PATENT OFFICE

109,959

DESIGN FOR AN AIRPLANE

Alexander P. de Seversky, Asharoken Beach,
Northport, N. Y., assignor to Seversky Aircraft
Corporation, a corporation of Delaware

Application November 9, 1937, Serial No. 72,716

Term of patent 14 years

To all whom it may concern:

Be it known that I, Alexander P. de Seversky, a citizen of the United States, residing at Asharoken Beach, Northport, Suffolk County, New York, have invented a new, original, and ornamental Design for Airplanes, of which the following is a specification, reference being had to the accompanying drawings, forming a part thereof.

Of these drawings,

Fig. 1 is a three-quarter rear perspective view of an airplane showing my new design;

Fig. 2 is a front elevation thereof;

Fig. 3 is a top plan view thereof, and

Fig. 4 is a side-elevation thereof.

I claim:

The ornamental design for an airplane, substantially as shown.

ALEXANDER P. DE SEVERSKY.
